UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,322,316.

Specification of Letters Patent. **Patented Nov. 18, 1919.**

Application filed September 22, 1915, Serial No. 51,981. Renewed September 20, 1917. Serial No. 192,307.

To all whom it may concern:

Be it known that I, RONALD A. McCANN, a citizen of the United States, residing at Swissvale, in the county of Allegheny and

5 State of Pennsylvania, have invented certain new and useful Improvements in Railway Signaling, of which the following is a specification.

10 My invention relates to railway signaling; it is particularly adapted to signaling for passing sidings between stretches of track over which traffic moves in both directions, although it is not limited to this particular application.

15 I will describe one form of railway signaling system embodying my invention and then point out the novel features thereof in claims.

20 In the accompanying drawings, Figure 1 is a diagrammatic view showing a stretch 25 of single track with passing sidings and a plurality of signals for governing traffic through the stretch in both directions. Fig. 2 is a diagrammatic view showing one form and arrangement of circuits for the control 25 of signal 5 in Fig. 1 and embodying my invention.

Similar reference characters refer to similar parts in each of the views.

Referring first to Fig. 1, A—H is a stretch 30 of single track between two passing sidings M and O over which traffic moves in both directions. Adjacent the middle of stretch A—H is another passing siding N whereby stretch A—H is divided into two blocks, 35 A—D and E—H extending respectively from siding M to siding N and from siding N to siding O. Traffic through block H—E from east to west is governed by signals 1, 3 and 5, located at intervals through the 40 block, and traffic through the block from west to east is governed by other signals 8, 6 and 4. Traffic through block D—A is similarly governed by signals 9, 11 and 13 and by signals 16, 14 and 12. Signals 7 45 and 10 govern entrance into siding N from east and west respectively. As here shown each signal is of the three position type, capable of giving three indications; namely, "proceed" when the semaphore arm is vertical, "caution" when the semaphore arm is

inclined, and "stop" when the semaphore arm is horizontal. It is understood, however, that I do not limit myself to this particular kind of signal.

Blocks A—D and E—H are divided by 55 insulated joints 2 into several successive sections, A—B, B—C, C—D, and E—F, F—G, G—H respectively, and as here shown a pair of opposing signals is located near each junction of adjacent sections, although I do 60 not wish to be limited to this particular location of signals. The signals for block A—D are so controlled that when a train moving toward the east enters this block, signal 9 is placed at "stop" and is held 65 there until the train passes out of the block, thus prohibiting a westbound train from entering the block while the eastbound train is anywhere in the block. As the eastbound train enters the block, it also causes signal 70 16 to indicate "stop", and as it passes signals 14 and 12 these signals are successively caused to change to "stop" indication. When the entire train passes out of section A—B, signal 16 changes to the "caution" indica- 75 tion, and when the entire train passes out of section B—C, this signal returns to the full "proceed" indication. Signal 14 changes to "caution" when the train leaves section B—C, and to "proceed" when the train 80 leaves section C—D. Two or more trains may, therefore, follow each other through the block under the same signal protection as is customarily provided on double track roads. Similarly, when a westbound train 85 enters block A—D, signals 9, 12, 14 and 16 are placed at stop, and signal 9 subsequently changes successively to "caution" and "pro- 90 ceed." Signal 11 changes to stop when it is passed by the train, and subsequently changes to "caution" and "proceed" suc- 95 cessively.

The signals for block E—H are controlled in the same manner as the signals for block A—D.

100 The operation of the signals which I have just outlined may be accomplished by several different arrangements of apparatus and circuits, such, for example, as the arrangements shown in Letters Patent of the

United States, Nos. 1204998 and 1233488, granted to me on Nov. 14, 1916, and on July 17, 1917, respectively. I do not wish to be limited, however to any particular arrangements of apparatus and circuits for accomplishing this signal operation.

Whenever signal 9 indicates "stop," signal 7 indicates "caution," and whenever signal 7 indicates "stop," signal 5 indicates "caution." The manner in which this control is accomplished will be explained hereinafter. It is desirable, however, that when an eastbound train occupies block A—D, signal 5 as well as signal 7 should indicate "caution," but that when a westbound train has passed signal 9, thus allowing signal 7 to change to "caution," signal 5 should return to the full "proceed" position. The reason for this is as follows: Assume that signal 5 indicates proceed while signal 9 is at stop, and that two trains moving in opposite directions approach siding N. If the eastbound train should pass signal 9 just after the westbound train had passed signal 5 (indicating proceed), the westbound train would receive a stop indication at signal 7 without having been previously warned by a caution indication at signal 5. However, if two westbound trains are moving along the track from H to A, it is desirable that signal 5 should change to proceed indication as soon as the first train has passed signal 9, in order to avoid any unnecessary delay to the second train by a caution indication at signal 5.

The object of the present invention is the provision of novel and simple means for accomplishing the desired control of signal 5.

Referring now to Fig. 2, track section D—E is provided with a track circuit comprising a battery *b*, the track rails and a track relay *T*¹⁰. Track section E—F is divided into two sub-sections E—L and L—F, which sub-sections are provided with track circuits comprising track relays *T*⁸ and *T*⁵, respectively. The track section to the left of location D is provided with a track circuit which includes a track relay *T*⁹. Adjacent signal 7 are located a signal relay *R*⁷, a polarized relay *P*⁷ and an auxiliary relay *X*⁷ for purposes to be pointed out hereinafter. Each relay *R*⁷ and *P*⁷ is so constructed that when the polar contacts have been shifted to one extreme position by current of one polarity, they remain in such position, even after the relay is deenergized, until the relay becomes energized by current of the opposite polarity. Signal 7 is provided with a pole changer *W*⁷, and a circuit controller *V*⁷ which has three contacts *m*, *n* and *o*. Contact *m* is closed at both proceed and caution indications of signal 7 and also while the semaphore blade is moving between these two indications; contact *n*

is closed only while the semaphore is between the caution and stop indications; and contact *o* is closed only when the signal is indicating "caution."

Relay *R*⁷ is controlled by pole changer *W*⁹ of signal 9 and by track relay *T*¹⁰, the circuit being: from battery *Z*⁹, through wire 70, pole changer *W*⁹, wire 71, contact 72 of relay *T*¹⁰, wire 73, relay *R*⁷, wire 74, pole changer *W*⁷, and wire 75 to battery *Z*⁹. When signal 9 is indicating "proceed" circuit controller *W*⁹ is in the position shown, and relay *R*⁷ is energized by current of normal polarity, so that it closes polarized contacts 76 and 77.

Relay *X*⁷ is controlled by relay *R*⁷ and contact *m* of controller *V*⁷, the circuit being: from the positive terminal of battery *Z*⁷, through wire 81, contact *m* of controller *V*⁷, wire 80, contact 76 of relay *R*⁷, relay *X*⁷, wires 79 and 78 to the negative terminal of battery *Z*⁷.

The caution indication of signal 7 is controlled by relay *R*⁷ through the following circuit: from battery *Z*⁷, through wires 81 and 88, front contact 87 of relay *R*⁷, wires 86 and 85, operating mechanism of signal 7, wire 84, front contact 83 of relay *R*⁷, wires 82 and 78 to battery *Z*⁷.

The proceed indication of signal 7 is controlled jointly by relays *R*⁷ and *X*⁷, the circuit being the same as the caution indication circuit up to and including wire 86, then through wire 91, contact 90 of relay *X*⁷, wire 89, operating mechanism of signal 7, wire 84, front contact 83 of relay *R*⁷, wires 82 and 78 to battery *Z*⁷.

Relay *R*⁷ and controller *V*⁷ enter into the control of relay *P*⁷. The contacts of this relay are operated to the normal position (in which they are shown on the drawing) by current flowing in the circuit: from the positive terminal of battery *Z*⁷, through wires 81 and 96, contact *o* of controller *V*⁷, wire 95, front contact 94 of relay *R*⁷, contact 77 of relay *R*⁷, wire 93, relay *P*⁷, wire 92 to the middle terminal of battery *Z*⁷. The contacts of relay *P*⁷ are reversed by current through the circuit: from the middle point of battery *Z*⁷, through wire 92, relay *P*⁷, wire 93, contact 77 of relay *R*⁷, lower contact 94 of relay *R*⁷, wire 97, contact *n* of controller *V*⁷, wire 78 to the negative terminal of battery *Z*⁷.

Relay *R*⁵ is controlled by the track relays of section E—F, by relay *P*⁷ and—according as relay *P*⁷ is normal or reversed—by relay *X*⁷ or pole changer *W*⁷. With the apparatus in the positions shown in the drawing, relay *R*⁵ is energized by current in the circuit: from the positive terminal of battery *Z*⁷, through wires 81 and 101, front contact 102 of relay *X*⁷, wire 106, contact 107 of relay *P*⁷, wire 104, contact 109 of relay

T^s, wire 113, contact 110 of relay T^s, wire 111, energizing winding of relay R^s, wire 112, contact 108 of relay P^r, wire 114, front contact 103 of relay X^r, wires 115 and 78 to the negative terminal of battery Z^r. When relay X^r is deenergized so that its contact fingers 102 and 103 engage their respective back contacts, the current in this circuit is reversed (as evident from the drawing) so that relay R^s opens contact 23. When relay P^r is reversed the circuit for relay R^s is as follows: from the positive terminal of battery Z^r, through wires 81 and 116, pole changer W^r, wire 117, contact 107 of relay P^r, wire 104, contact 109 of relay T^s, wire 113, contact 110 of relay T^s, wire 111, relay R^s, wire 112, contact 108 of relay P^r, wire 118, pole changer W^r, wires 119 and 78 to the negative terminal of battery Z^r. The direction of current in this circuit is controlled by pole changer W^r in the same way as the direction of current in the first described circuit for relay R^s is controlled by relay X^r.

Signal 5 is controlled by relay R^s through the medium of circuits which are obvious from the drawing, and the same thing is true as to the control of signal 9 by relay R^r.

To explain the operation of this system of signaling, suppose that a car or train travels from F to D. As the train enters section F—L it deenergizes relay T^s, which opens at contact 110 the circuit for relay R^s, so that signal 5 is put to the stop indication.

When the train enters section L—E it deenergizes relay T^s which causes at contact 109 another break in the circuit for relay R^s, so that relay R^s remains deenergized even when the train leaves section L—F and causes relay T^s to close its front contacts. When the train enters section E—D, track relay T¹⁰ is deenergized and opens the circuit for relay R^r which in turn opens at contact 83 and 87 both the proceed and caution indication circuits of signal 7, so that this signal moves to the stop indication. Relay P^r is reversed during this movement of the signal because back contact 94 of relay R^r is closed, so that the reverse energization circuit for relay P^r is momentarily completed as a finger of circuit controller V^r sweeps over segment n. Relay P^r accordingly reverses its contacts 107 and 108 so that the control circuit of relay R^s is led through pole changer W^r by means of wires 117 and 118 (this circuit has been traced hereinbefore). Signal 7 reverses pole changer W^r as it changes its indication. Consequently, when the train leaves sub-section E—L completely, so that relay T^s is reenergized and completes the circuit of relay R^s, the latter relay is energized reversely. As a result, the front contacts of relay R^s are closed, whereas polarized contact 23 is opened so

that signal 5 is caused to indicate "caution." 65 When the train enters the track section governed by signal 9, it causes signal 9 to indicate "stop" by opening track relay T⁹. Signal 9 reverses pole changer W⁹ so that, when the train leaves section D—E completely 70 and causes relay T¹⁰ to close at contact 72 the circuit for relay R^r, the latter relay is energized in the reverse direction. Consequently, signal 7 moves to the caution indication and changes pole changer W^r to normal. 75 The direction of flow of current in relay R^r is thus changed to normal, so that contact 23 is closed and signal 5 is caused to indicate "proceed." When the train passes out of the section governed by signal 80 9, this signal assumes the caution indication and changes pole changer W⁹ to normal. Current then flows through relay R^r in the normal direction so that it closes at contact 76 the circuit for relay X^r. This relay 85 closes its front contacts 90, 102 and 103. Contact 90 closes the proceed indication circuit of signal 7. However, before the signal actually moves from the caution position, relay P^r has been brought back to the normal position shown in Fig. 3 by current in 90 its normal energization circuit, which is closed at contact o of controller V^r and contacts 94 and 77 of relay R^r. The contacts of relay P^r are thus returned to the normal position shown in Fig. 3, so that the circuit of relay R^r is transferred from pole changer W^r to contacts 102 and 103 of relay X^r. Relay X^r being energized, the current continues to flow through the circuit of relay 100 R^r in normal direction so that signal 5 remains unaffected. When signal 7 leaves its caution position it opens at contact o of controller V^r the circuit for relay P^r. This relay remains in the normal position even 105 though deenergized, as pointed out hereinbefore. The circuit for relay X^r remains unbroken when signal 7 moves to the proceed aspect because its circuit is closed through contact m. 110

A train movement in the reverse direction, i. e. from west to east causes the following operation of the apparatus. As soon as the train enters block A—D (Fig. 1) from siding M, it causes opposing signals 115 13, 11 and 9 to assume the stop indication. As signal 9 changes its indication, pole changer W⁹ reverses the current through relay R^r. Reversal of current causes this relay to drop its neutral contact fingers, then reverse its polar contact fingers and finally pick-up its neutral contact fingers. The opening of the front contacts 87 and 83 of relay R^r opens the holding circuit for signal 7, so that this signal begins to change 120 its indication. The opening of front contact 94 of relay R^r opens the circuit of relay P^r. However, this has no effect on the lat-

ter relay because no current has been flowing in the relay winding, the circuit having been open at contact *o* of pole changer V^7 . Neither has the subsequent closure of back contact 94 of relay R^7 any effect on relay P^7 , because the circuit of which this contact is a member, is open at contact *n* of controller V^7 . For similar reasons the opening of polarized contact 77 of relay R^7 has no effect on relay P^7 . The opening of polarized contact 76 of relay R^7 breaks the circuit of relay X^7 so that its contacts drop causing results which I shall explain below. When the neutral front contacts of relay R^7 are again closed they complete at contacts 87 and 88 the caution circuit for signal 7, so that this signal is arrested as it reaches the caution position. The closure of front contact 94 of relay R^7 again has no effect on relay P^7 because this circuit is open at polarized contact 77. Relay X^7 is now deenergized, as mentioned above, so that contacts 102 and 103 have reversed the current in the circuit for relay R^5 . Polarized contact 23 of relay R^5 is, therefore, reversed so that signal 5 goes to the caution indication.

To summarize, the entrance of a train into block A—D from siding M (Fig. 1) causes not only a stop indication of the opposing signals 13, 11 and 9 of block A—D, but also a caution indication of signals 7 and 5 which govern the entrance into siding N from the opposite direction. If there were a west-bound train in block E—H, the engineer of that train would thus be duly warned at signal 5 of the approach of the east-bound train to siding N. The engineer of the east-bound train would receive a similar warning by finding signals 12 and 10 at "caution"—due to a similar operation of apparatus which would have been caused by the entrance of the west-bound train into block E—H. The engineers of the trains would thus be prepared to pass each other at siding N in accordance with the rules and regulations of the railroad. If the east-bound train were the superior train it would be allowed to remain on the straight track within siding limits, whereas the west-bound train or inferior train would be switched off to the siding track.

Assuming that the east-bound train has reached the entrance to siding N, it causes the following operation of the signal apparatus as it passes through the siding limits: Track relay T^{10} is deenergized as the train enters section D—E, so that signal 10 (which is controlled similarly to signal 7) is deenergized and assumes the stop indication. Relay T^{10} opens at contact 72 the circuit for relay R^7 , which therefore opens its front contacts and closes its back contacts. Of course, the polarized contacts 76 and 77 of relay R^7 remain open. The opening of front contacts 87 and 88 of relay R^7 breaks

the holding circuit for signal 7, so that the signal moves to the stop indication. Closure of back contact 94 of relay R^7 has no effect on relay P^7 because its circuit is open at contact 77 of relay R^7 . As the rear end of the train leaves section C—D all signals in block A—D assume the proceed indication (provided there is no other train in the block). As signal 9 resumes its proceed aspect it changes pole changer W^9 back to its normal position. Although this changes to normal the polarity of the connection of battery Z^9 to the line circuit of relay R^7 , this relay is not affected thereby until the train has completely left section D—E, because its circuit is open at relay T^{10} . As the train enters section E—L it deenergizes track relay T^8 , so that signal 8 changes to the stop indication. Track relay T^8 opens at contact 109 the circuit for relay R^5 so that signal 5 is caused to indicate stop. By means of the control hereinbefore referred to, signals 3 and 1 of block E—H (Fig. 1) also assume the stop indication. When the rear end of the train leaves section D—E, relay T^{10} is reenergized and closes at contact 72 the circuit for relay R^7 , so that current of normal polarity is sent through the relay winding. This causes successively the closure of the polarized contacts and the neutral front contacts. Contact 76 of relay R^7 closes the circuit for relay X^7 , but this relay is not energized because its circuit is open for the time being at contact *m* of controller V^7 . Neither does the closure of contact 77 have any effect on relay P^7 because during the fractional time interval before neutral back contact 94 of relay R^7 opens, the reverse circuit of relay P^7 is open at contact *n*, and when front contact 94 of relay R^7 is closed, the normal circuit of relay P^7 is open at contact *o*. Closure of front contacts 87 and 88 of relay R^7 closes the caution indication circuit of signal 7, so that signal 7 moves to the caution position. During this movement, signal 7 changes pole changer W^7 to normal. This is irrelevant, however, to the operation of other apparatus because pole changer W^7 is disconnected at the contacts of relay P^7 from the circuit of relay R^5 . As soon as the signal reaches the caution position, contact *m* of controller V^7 completes the circuit of relay X^7 so that this relay opens its back and closes its front contacts. Closure of contact 90 of relay X^7 completes the proceed indication circuit of signal 7, so that it moves to the proceed indication. Contacts 102 and 103 change to normal the connections of battery Z^7 to the control circuit of relay R^5 , so that this relay will be energized by current of normal polarity when its circuit is closed later on at track relay T^8 . Thus all apparatus located adjacent signal 7 has been returned to the position shown in the drawing.

Although I have in Fig. 2 shown one specific arrangement of apparatus and circuits for accomplishing the desired control of the signals, it is understood that my invention is not limited to this specific arrangement, but that it may be applied to any arrangement of apparatus and circuits for accomplishing this same control of the circuits.

10 Where in the accompanying claims I have used the expression "three sections," or "three successive sections," the sections referred to are sections E—F, D—E and C—D, these being the first, second and third sections respectively. The signals referred to in the claims for these sections are signals 5, 7 and 9.

15 Although I have herein shown and described only one form of railway signaling system embodying my invention, it is understood that various changes and modifications may be made therein within the scope of the appended claims without departing from the spirit and scope of my invention.

20 Having thus described my invention, what I claim is:

25 1. In combination, a stretch of railway track comprising three successive sections, a signal for the first section, means for governing said signal, said means comprising means responsive to the presence or absence of a car or train in the second section, means responsive to the presence or absence of a train in the third section, and means responsive to the direction of the passage of a train through the stretch for selecting between the two last mentioned means.

30 2. In combination three successive sections of a railway track, a track relay for each section, a signal for the first section, means controlled by the track relay of the third section and adapted to control said signal, means controlled by the track relay of the second section and adapted to control

35 said signal, and means controlled by said track relays for selecting between said means adapted to control said signal.

40 3. In combination, three successive sections of a railway track, a signal for the first section, a track relay for each section, means for the second section and means for the third section governed by said track relays for at times controlling said signal, and a device controlled by said track relays for selecting between said means.

45 4. In combination, a stretch of railway track comprising three successive sections, track relays for the second and third sections, a signal for the first section, means controlled by one track relay for controlling the signal, means controlled by the other track relay for controlling the signal, and means controlled by said track relays for selecting between said means for controlling

55 the signal.

5. In combination, an advance section and a rear section of railway track, a track relay for each section, a signal, means governed by the track relay of the advance section adapted to control said signal, means governed by the track relay of the rear section adapted to control said signal, and means responsive to reversals of current and controlled by said track relays for selecting between said means adapted to control said signal.

6. In combination, an advance section and a rear section of railway track, a track relay for each section, a signal, means governed by the track relay of the advance section adapted to control said signal, means governed by the track relays of both sections adapted to control said signal, and means controlled by said track relays for selecting between said means adapted to control said signal.

7. A stretch of railway track comprising an advance and a rear section, a track relay for each section, a relay comprising neutral and polarized armatures responsive respectively to the track relays of the rear and advance sections, a signal, means controlled by said neutral armature for at times controlling said signal, means controlled by both of said armatures for at times controlling said signal, and means responsive to the direction of traffic through said stretch for selecting between said means for controlling said signal.

8. In combination, a stretch of railway track, three successive signals, 5, 7, and 9, track circuits including track relays for the control of said signals, a pole-changer controlled by signal 9, a pole-changer controlled by signal 7, and means controlled by said track relays in accordance with the sequence in which they are operated for controlling signal 5 by one or the other of said pole-changers.

9. In combination, a stretch of track comprising three sections, a track relay for each section, a signal located at the entrance to each section, means for governing the third signal by the track relay of the third section, means for governing the second signal by the third signal and the track relay of the second section, means for governing the first signal by the second signal and the track relay of the third section, and means responsive to reversals of current for at times changing the control of said first signal from the second signal to the third signal.

10. In combination, a stretch of railway track comprising three sections, a signal located adjacent the entrance to each section, a track relay for each section, means for controlling the third signal by the track relay of the third section, a polarized relay comprising a neutral and a polarized armature,

means for controlling the second signal by the polarized relay, an auxiliary relay controlled by the polarized relay and by the second signal, a translating device responsive to reversals of current, means for controlling said device by the polarized relay and the second signal, a circuit for the first signal controlled by said first track relay, and means controlled by said device for 10 controlling said circuit either by said second signal or by said auxiliary relay.

11. In combination, a stretch of railway track, two successive signals governing traffic thereover, a relay responsive to reversals of current for controlling the first signal, said first signal indicating clear or caution according as said relay is normally or reversely energized, and means controlled by a train passing over said stretch for causing said relay to be normally or reversely energized when the second signal indicates caution according as said train is moving in the direction governed by said signals or in the opposite direction.

12. In combination, a stretch of railway track, two signals governing traffic thereover in one direction, a polarized relay for controlling the first of said signals whereby said signal indicates clear or caution according as said relay is energized in normal or reverse direction, and means controlled by a train passing along said stretch for causing said relay to be positively energized when the second signal indicates caution and the train is moving in the direction governed by said signals, and for causing said relay to be reversely energized when the second signal indicates caution and the train is moving in the opposite direction.

13. In combination, a stretch of railway track divided into three successive sections, a signal for the first section arranged to indicate stop, caution and proceed, said signal indicating proceed when not affected by the presence of trains, means controlled by a train in the third section for causing said signal to indicate caution, and train-controlled means operated by a train entering the second section moving toward the third 50 for removing said signal from control by a train in the third section whereby when the latter train occupies the third section said signal may indicate proceed.

14. In combination, a stretch of railway track divided into three successive sections, a signal for the first section arranged to indicate stop, caution and proceed, said signal indicating proceed when not affected by the presence of trains, means controlled by a train in the third section for causing said signal to indicate caution, and train-controlled means set in operative condition by a train entering the second section moving toward the third and maintained in such 60 condition until the train leaves the third sec-

tion for removing said signal from control by a train in the third section whereby when the train occupies the third section the signal may indicate proceed.

15. In combination, a stretch of track 70 divided into three successive sections, a signal for the first section, a caution indication circuit and a proceed indication circuit for said signal, the latter circuit being closed when the signal is not affected by the presence of trains, means controlled by a train in the third section for opening the proceed circuit and closing or holding closed the caution circuit, and means controlled by a train entering the second section moving 80 toward the third for removing said proceed circuit from control by said first-mentioned means whereby when the latter train occupies the third section the signal may indicate proceed.

16. In combination, a stretch of railway track comprising three sections, a first and a second signal for the first and second of said sections respectively, a first and a second signal relay each responsive to reversals 90 of current for controlling said first and second signals respectively whereby each signal indicates proceed or caution according as the corresponding relay is energized in normal or reverse direction, train-controlled 95 means for causing the second signal relay to be energized in reverse or normal direction according to the presence or absence of a train in the third section, a pole-changing relay for at times controlling the first signal 100 relay so that such signal relay is energized in normal or reverse direction according as the pole-changing relay is energized or de-energized, a pole-changer operated by the second signal for at other times controlling the 105 first signal relay so that such signal relay is energized in normal or reverse direction according as the second signal indicates caution or stop, means controlled by the second signal relay for energizing the pole-changing 110 relay when the second signal relay is energized in normal direction but not when it is energized in reverse direction, a directional relay for connecting said first signal relay with said pole-changing relay or with 115 said pole-changer according as the contacts of the directional relay are in normal or reverse position, and means controlled by said second signal relay for energizing said directional relay in such direction that its 120 contacts assume the reverse position when a train moving in the direction in which said signals govern traffic enters the second section, and for energizing the directional relay in the reverse direction when such 125 train leaves the third section.

17. In combination, a stretch of railway track comprising three sections, a first and a second signal for the first and second of said sections respectively, a first and a 130

second signal relay each responsive to reversals of current for controlling said first and second signals respectively whereby each signal indicates proceed or caution according as the corresponding relay is energized in normal or reverse direction, train controlled means for causing the second signal relay to be energized in reverse or normal direction according to the presence or absence of a train in the third section, a pole-changing relay for at times controlling the first signal relay so that such signal relay is energized in normal or reverse direction according as the pole-changing relay is energized or deenergized, a pole-changer operated by the second signal for at other times controlling the first signal relay so that such signal relay is energized in normal or reverse direction according as the second signal indicates caution or stop, means controlled by the second signal relay for energizing the pole-changing relay when the second signal relay is energized in normal direction but not when it is energized in reverse direction, and means controlled by a train passing through said sections in the direction in which said signals govern traffic for controlling said first signal relay with the pole-changer when the train enters the second section and with the pole-changing relay when such train leaves the third section, said first signal relay remaining connected with the pole-changing relay during the passage of a train in the opposite direction through said sections.

18. In combination, a stretch of railway track comprising three sections, a first and a second signal for the first and second of said sections respectively, a first and a second signal relay each responsive to reversals of current for controlling said first and second signals respectively whereby each signal indicates proceed or caution according as the corresponding relay is energized in normal or reverse direction, train controlled means for causing the second signal relay to be energized in reverse or normal direction according to the presence or absence of a train in the third section, a pole-changing relay for at times controlling the first signal relay so that such signal relay is energized in normal or reverse direction according as the pole-changing relay is energized or deenergized, a pole-changer operated by the second signal for at other times controlling the first signal relay so that such signal relay is energized in normal or reverse direction according as the second signal indicates caution or stop, means controlled by the second signal relay for energizing the pole-changing relay when the second signal relay is energized in normal direction but not when it is energized in reverse direction, and train governed means for causing said first signal relay to

be controlled by said pole-changer or by said pole-changing relay according as a train is moving in the direction in which said signals govern traffic or in the opposite direction.

70

19. In combination, a stretch of railway track divided into three successive sections, a signal for the first section adapted to indicate stop, caution and proceed, a second signal for the second section, a line relay responsive to reversals of current for controlling said second signal, train controlled means for deenergizing said line relay when a train occupies said second section and for energizing said line relay in normal or reverse direction according as the third section is free or occupied, means controlled by said line relay for causing said signal for the first section to indicate proceed or caution according as the relay is energized in normal or reverse direction, and means controlled by said line relay when deenergized by a train entering the second section moving toward the third section for removing said signal from control by said relay to the extent that the signal may subsequently indicate proceed when the relay becomes reversely energized due to the passage of such train into the third section.

20. In combination, a stretch of railway track divided into three successive sections, a signal for the first section adapted to indicate stop, caution and proceed, a relay responsive to reversals of current, train controlled means for deenergizing said relay when a train occupies the second section and for energizing said relay in normal or reverse direction according as the third section is free or occupied, means controlled by said relay for causing said signal to indicate proceed or caution according as the relay is energized in normal or reverse direction, and means controlled by said line relay when deenergized by a train entering the second section moving toward the third for removing said signal from control by said relay to the extent that the signal may subsequently indicate proceed when the relay becomes reversely energized due to the passage of the train into the third section.

21. In combination, a stretch of railway track divided into three successive sections, a signal for the first section adapted to indicate stop, caution and proceed, a relay responsive to reversals of current, train controlled means for deenergizing said relay when a train occupies the second section and for energizing said relay in normal or reverse direction according as the third section is free or occupied, means controlled by said relay for causing said signal to indicate proceed or caution according as the relay is energized in normal or reverse direction, an auxiliary relay for removing said signal from control by said first relay to the extent

that the signal may indicate proceed when the first relay is energized in reverse direction, and means controlled by said first relay for actuating said auxiliary to exercise its
5 said control when the first relay is deenergized by a train entering the second section moving toward the third, and for restoring said auxiliary to its original condition when the first relay becomes energized in normal

direction due to the passage of the latter 10 train out of the third section.

In testimony whereof I affix my signature in presence of two witnesses.

RONALD A. McCANN.
